CONTAINER FOR A PAINT SPRAYER OR THE LIKE

Joseph L. Terrels, 6 Greenbank Ave., and Robert
Meneses, 1308 West Chester Pike, both of West
Chester, Pa. 19380

Filed Oct. 25, 1968, Ser. No. 14,182

Term of patent 14 years

Int. Cl. D23—01

U.S. Cl. D23—2

The broken line representation of a spray gun in FIGURE 1 is for purposes of illustration only.

We claim:

The ornamental design for a container for a paint sprayer or the like; substantially as shown and described.
